UNITED STATES PATENT OFFICE

ORVILLE B. SHAHAN, OF TUNNELTON, WEST VIRGINIA

FISHPLATE WITH LUGS

Application filed November 11, 1929. Serial No. 406,460.

This invention relates to certain new and useful improvements in railroad tie and fish plate construction.

An object of the invention contemplates the provision and arrangement of fish plates disposed upon the ends of the tie.

A further object of the invention embodies a coupling plate for the rail joint upon the tie.

More specifically stated the coupling plates and initial fish plates are shaped to accommodate wedge members therebetween to shift the assembled rail joint toward the swingably mounted fish plates to prevent turning thereof and to align the ends of the meeting rails.

With the above and other objects in view, the invention further consists of the following novel features and details of construction, to be hereinafter more fully described, illustrated in the accompanying drawings and pointed out in the appended claims.

In the drawings:

Figure 1 is a top plan view of the invention as applied and in use.

Figure 2 is a horizontal sectional view taken on line 2—2 of Figure 1.

Figure 3 is a fragmentary longitudinal sectional view taken through one of the ties.

Figure 4 is a view similar to Figure 2 taken from the opposite side of the joint.

Figure 5 is a perspective view of the fish plate.

Referring to the drawings in detail where-in like characters of reference denote corresponding parts, the reference character 10 indicates my especial form of tie having depending side flanges 11 throughout the entire length thereof. The ends of the tie are upwardly and inwardly curved in the manner shown in Figure 3 of the drawing to provide semi-circular cup-shaped members 12. Fish plates of the configuration designated and as indicated at 13 in Figure 5 of the drawings are provided with upstanding portions 14 engageable with the webs of rail members and long enough to extend for appreciable distances beyond the break or meeting ends of companion rail members. Flange portions 15 downwardly and obliquely disposed from

the lower edges of the upstanding flange portions 14 are engageable with the upper sides of the rail feet in the manner shown in Figure 3. Ears 16 carried by and downwardly converging at spaced intervals from the outer edge and adjacent the ends of the flange 15, are designed to accommodate the immediate portions of the cup-shaped members 12 therebetween. Pin members 17 arranged in pairs upon the upstanding flange portions 15 of the fish plates 13 are projected through openings in the webs of adjacent rails as substantiated in the Figure 3 illustration.

The pin members 17 fit snugly in openings provided in the web 14 of the plate 13 and the heads of the said pin members 17 lie at the side of the web 14.

Fish plates of the configuration shown and identified by the reference numeral 18 are of channel formation and disposed in substantially inverted positions upon the upper surfaces of the rail ties and adjacent the rail joints thereon. Studs or rivet members, such as indicated at 19, extended through the immediate overlapping portions of the tie and fish plates 18 whereby the latter may be aligned to dispose the outermost upwardly and obliquely disposed extremities 20 thereof evenly across the break or rail joint.

After the joints have been assembled in the manner shown and described, it is necessary to establish some means of connection between the cup-shaped members 12 and the fish plates 13 to prevent the rails from spreading. This connection is completed through the employment of wedge members 21 longitudinally tapered, as at 22, upon the outer rounded sides thereof in conformity with the interior surfaces of the cup-shaped members 12 whereas the innermost sides of the wedge members are provided with successive communicating longitudinally extending facets 23 designed to engage the upper and outer surfaces of the flange members 15, the flanges 14 and to free the corner portions of the heads or balls of the rails whereby the latter will be free to flex an appreciable distance when a train of cars 100

passes thereover whereby the latter will pursue a more nearly straight course.

In assembling a rail joint upon the present form of tie construction, the fish plates 18 are swung to occupy positions at right angles to the tie proper. The abutting ends of rail members are then laid upon the upper side of the tie proper and the fish plates retracted to occupy positions in alignment with the tie to dispose the outermost upwardly and obliquely disposed extremities 20 thereof evenly across the meeting ends of the rails. The fish plates 13 are then assembled projecting the pins 17 thereof through the webs of the rails upon opposite sides of the joints; the ears 16 straddling the intermediate portions of the channel-shaped members 12. The wedge members 21 are then driven home and the rails will be forced inwardly and tightly 20 against the adjacent extremities of the fish plates 18.

The ends of the pin members 17 fit snugly in openings provided at the ends of the abutting rails and when the wedge 21 is applied it 25 bears against the heads of the pins 17 and holds the parts firmly in place.

It is believed that in the application of the present form of rail joint comprising the several parts alluded to in the foregoing comprising a joint of such character as may be readily assembled with the use of a sledge hammer and then only in the shifting of the fish plates 18 and the wedge members 21, and the joint established across the meeting ends 35 of adjacent rail members will be securely held against displacement in both directions.

The invention is susceptible of various changes in its form, proportions and minor details of construction, and the right is here- 40 in reserved to make such changes as properly fall within the scope of the appended claim.

Having described the invention, what is claimed is:—

A fish plate structure adapted to be applied to the web portions of abutting rails, and a supporting tie, comprising a plate body provided at its base flange with spaced ears adapted to lie at the sides of the tie, said body having a flange portion provided with 45 spaced openings adapted to register with corresponding openings in the web portions of the rails, pins passing through said openings and fitting snugly therein and having heads lying at the side of the web portion of the body, a wedge adapted to bear against said pins and means for holding the wedge upon the web of the body and pins.

In testimony whereof I affix my signature.
ORVILLE B. SHAHAN.
